UNITED STATES PATENT OFFICE.

HOWARD K. KING, OF PHILADELPHIA, PENNSYLVANIA, ASSIGNOR
TO CHAMBERS BROTHERS COMPANY, A CORPORATION OF PENN-
SYLVANIA.

CUTTING MECHANISM FOR FOLDING-MACHINES.

No. 804,476.

Specification of Letters Patent.

Patented Nov. 14, 1905.

Application filed August 23, 1904. Serial No. 221,882.

To all whom it may concern:

Be it known that I, HOWARD K. KING, a citizen of the United States, residing at Philadelphia, in the county of Philadelphia and State 5 of Pennsylvania, have invented a new and useful Cutting Mechanism for Folding-Machines, of which the following is a specification.

My invention relates to cutting mechanism for folding-machines.

10 The object of my invention is to provide improved means for incising or cutting the sheet at intervals along the line of the proposed fold, the purpose of which, as is well known in the art, is to prevent the buckling 15 or wrinkling of the sheets when a number of sheets are folded together in two directions and also to facilitate the separation of the outer edges of the sheet when the same are formed into a pamphlet or book.

20 My invention comprises simple and efficient means for securing a clean cut by the shearing action of the cutting-knife in coöperation with the supporting-plate over which the sheet passes.

25 My invention comprises simple and efficient means for holding the sheet firmly to the supporting-plate during the cutting operation.

30 My invention comprises means whereby the sheet is bent to cause the opening of the incisions to permit the release of the knife-points, and thereby facilitate the stripping of the sheet therefrom.

My invention also comprises various improvements in details of construction.

35 Referring to the drawings, Figure 1 is a plan view of a folding-machine comprising my improved means, portions being broken away to show parts which would otherwise be obscured. Fig. 2 is a cross-section on line 2 2 40 of Fig. 12. Fig. 3 is a side elevation of the machine in the preliminary position. Fig. 4 is a sectional elevation on line 4 4 of Fig. 1. Fig. 5 is a cross-section on line 5 5 of Fig. 4. Fig. 6 is a view similar to Fig. 4 with some 45 of the parts omitted. Fig. 7 is an enlarged cross-section of the slit mechanism and folding-rollers. Fig. 8 is a view similar to Fig. 6 with the parts in different positions. Fig. 9 is a cross-section, on an enlarged scale, of 50 the folding and cutting blades and slit mechanism in a slightly-different position from that shown in Fig. 8. Fig. 10 is a sectional ele-

vation on line 10 10 of Fig. 1. Fig. 11 is a plan view of the parts shown in Fig. 10. Fig. 12 is a sectional elevation on line 12 12 of Fig. 1. Fig. 13 is a plan view of the parts shown in Fig. 12. Fig. 14 is a side elevation of the parts shown in Figs. 12 and 13. Fig. 15 is a sectional view on line 15 15 of Fig. 1, the shaft, however, being shown solid. Fig. 16 is a diagrammatic view showing a sheet having one form of cuts or incisions. Fig. 17 is an elevation of the form of blades suitable for making the cuts or incisions shown in Fig. 16, the same, however, being on an enlarged scale. Fig. 18 is a diagrammatic view of a portion 60 of a sheet, showing another form of incisions. Fig. 19 is an elevation of a blade suitable for making the incisions shown in Fig. 18. Fig. 20 is a vertical section on line 20 20 of Fig. 19. Fig. 21 is an elevation of the clamping mechanism used in connection with the cutting-blade. Fig. 22 is a vertical cross-section on line 22 22 of Fig. 21.

Similar numerals refer to similar parts throughout the several views.

Folding-blade support and actuation.— Since my improved cutting means is adapted for use in connection with well-known forms of folding-machines, I confine the description of my invention to the parts peculiar thereto and such essential mechanism as may be necessary for applying the same to a folder, and as there may be a cutter working in connection with each fold it will only be necessary to describe one of these devices in detail and indicate the method of connecting up the others therewith.

Referring to Figs. 1 and 4, the folding-blade 1 is supported at the free ends of arms 1. These arms 1 are keyed to the sleeve 2, which 90 is loosely mounted on the shaft 3. The shaft 3 is journaled at each end in the stationary framework of the machine. The arms or extensions 5 and 32 are either integral with the arm 1 or so keyed to the sleeve 2 as to be rotatably rigid therewith. The cam-arm 4 is also mounted on the sleeve 2 and is adjustably locked in the desired angular position with respect to arm 1 by the set-screws 33 upon arm 32. The free end of arm or extension 5 is 95 pivotally secured to the spring-actuated rod 6. The cam-arm 4 is provided at its free end with the antifriction-wheel 4^a, which is adapted to engage with the periphery of cam 28, which 100

is mounted on shaft 28^a, said shaft being suitably geared with the other operating parts of the machine.

Cutting-blade support and actuation.—The 5 cutting-blade 13 is secured to the angle-iron 12, which is supported at the free ends of the arms 7. The arms 7 are keyed to the shaft 3. The arm 8 is also rotatably rigid with the shaft 3, having its free end pivotally connected 10 with the spring-actuated rod 10. This rod 10 is adapted to slide in the boss 11, connected with the framework of the machine, and is provided at its lower extension with the lock-nuts 10^a as adjustable means for limiting its 15 upward movement. A compression-spring surrounds the rod 10 and engages at one end the boss 11 and at the other end a collar secured to said rod. To arm 7 is adjustably secured by bolts operating in a slot the lug 9, 20 which is adapted to project over and engage with arm 1, thereby coupling said two arms together. By this means the movement of arm 7, due to the actuation of the spring-rod 10, is controlled by the cam-operated arm 1 until 25 after the cutting operation is completed. The movement of arm 7 is then arrested by the engagement of lock-nuts 10^a with boss 11, and the folding-blade on arm 1 continues its downward movement, independent of arm 7, to deliver 30 the sheet to the folding-rollers. Upon the upward or return movement of arm 1 the lug 9 is again encountered and the arm 7 is raised to the initial position. It will thus be seen that the cutter-arm 7 has no movement 35 independent of the folding-arm 1.

Sheet-pressing mechanism.—To the ends of the angle-iron 12 are secured the brackets 14, (see Figs. 2, 12, 13, and 14,) and in these brackets 14 are provided the ways 15. These 40 ways 15 are adapted to receive the plates 17, which are secured one at each end to the T-iron 16. These plates 17 are adapted to slide in the ways or channels 15, and consequently independent vertical movement will be permitted 45 between the angle-iron 12 and the T-iron 16. To the guide-plates 17 are secured the extensions 18, (see Figs. 13 and 14,) and to these extensions 18 are connected the tension-springs 19, whose other ends are secured 50 to studs 20, connected with the stationary part of the machine. The springs 19 normally hold extensions 18 against the brackets 14 of angle-iron 12 until the posts 21 are engaged by said extensions 18 upon the downward 55 movement of arms 1 and 7 and before the knife 13 enters the slit between members 34 and 35. The posts 21 project from the framework of the machine and are adapted to engage with the extensions 18 to limit the downward 60 spring-actuated movement of T-iron 16. Upon the return or upward movement of the cutting-knife 13 and its supporting angle-iron 12 from the position shown in Fig. 14 to the position shown, for example, in Fig. 4 the 65 bracket 14 engages the extension 18 to cause

the elevation of T-iron 16. It will be understood that during the engagement of 14 and 18 the members 12 and 16 are mechanically fixed. On the under side of the T-iron 16 are provided the bosses 22. Through these 70 bosses 22 extends rod 23, which supports sections 24 of rubber tubing. Upon the downward movement of the T-iron 16 these rubber sections 24 are adapted to be compressed against the sheet over plate 35, as and for the 75 purpose hereinafter described.

Slit mechanism.—The slit mechanism which is adapted to coöperate with the folding-blade and also with the cutting-blade is constructed as follows: The two parallel plates 34 and 35 80 are mounted on the angle-irons 25 and 26. The angle-irons 25 and 26 are provided at each end with axles 36 and 36^a and 37 and 37^a, which are journaled in the stationary framework of the machine. Upon the shaft 38, 85 which is suitably geared with the other operating parts of the machine, are mounted the cams 39 and 40. Cam 39 is adapted to engage with the antifriction-wheel 41, which is mounted on the free end of arm 42, which 90 is operatively rigid with the axle 36, so that the actuation of arm 42 by the rotation of cam 39 causes the rocking actuation of plate 34 of the slit mechanism against the pressure of spring 34^a. (See Fig. 1.) The cam 40 is 95 similarly adapted to engage and coöperate with the antifriction-wheel 43, secured to the the free end of arm 44, which is operatively rigid with axle 37, to cause the rocking actuation of the other plate 35 of the slit mechanism 100 against the pressure of spring 35^a. It will thus be seen that by a rotation of shaft 38 the plates 34 and 35 are rocked from the level position, as shown, for instance, in Figs. 6 and 10, to the open or tilted positions shown, 105 for instance, in Fig. 9 and back to the level position, and it will be obvious that by the well-known method of gears the rotation of shaft 38 may be so timed with the rotation of shaft 28^a of cam 28 that the rocking of 110 the slit mechanism will have the required relation with the reciprocative movement of the folding-blade, and consequently also of the cutter-blade.

In the device illustrated in the drawings I 115 have provided the shaft 38 and cams 39 and 40 in connection with a second slit mechanism of the machine and have connected the arms 42 and 44 of said slit mechanism by the connecting-rods 45 and 46 (see Figs. 3 and 10, 120 respectively) with similarly-mounted plates of the first slit mechanism, so that the operation of one slit mechanism will cause the operation of another slit mechanism.

The operation of my device is as follows: 125 Before the sheet traveling upon the tapes reaches the slit mechanism the cam 39 has reached such position as to tilt plate 35 of the slit mechanism shown in Fig. 10 or plate 34 of slit mechanism shown in Figs. 6 and 7 into 130

the position shown in Fig. 7—that is, with its edge toward the advancing sheet depressed below the plane of the other plate, so that said edge will not encounter the edge of the 5 advancing sheet and thereby obstruct it. The shape and actuation of the cam 39 are such that after the edge of the advancing sheet has passed over plate 34 or 35, as the case may be, the plate is brought back to the level position, 10 as shown in Figs. 4 and 10, so that said slit mechanism will be in condition for most efficient coöperation with the cutting-blade 13. When the sheet reaches the proper position on the tapes over the slit and folding-rollers, 15 the cam 28 has assumed such a position as will permit the downward movement of arm 1, bringing with it the arm 7, cutting-blade 13, and presser-rubbers 24. This serves first to compress the rubbers 24 upon the sheet over 20 the plate 35 until the projections 18 engage with post 21, as shown in Fig. 14. The knife then continues to descend until it reaches the position shown in Fig. 6, when the cutting operation has been completed. The further 25 movement of cam 39 and also of cam 40 now brings the plates 34 and 35 into the position shown in Fig. 8, when it will be noted the plate 35 has come clear of the presser-sections 24, so that the sheet is now free to travel with 30 the knife into the gradually-increasing slit between the tilted plates 34 and 35. No further cutting of the sheet by the knife 13 can take place after the release of the sheet by the presser-sections 24. The bending, 35 however, of the sheet into the slit by the knife 13 serves to open the incisions made by the knife in the sheet, so that the sheet may be readily disengaged from the knife. After the knife has come to rest because of the engagement of nuts 10^a with boss 11 the folding-blade 1^a continues to descend and strips 40 the sheet from the knife and carries down to the folding-rollers 29 and 30. It will be noted upon an inspection of Figs. 19 and 20 that 45 the serrated knife is beveled on one side only, so that the cutting edge of said knife will lie entirely in the plane of the other or flat side. Referring, for instance, to Fig. 6, it will be seen that the cutting edge of this knife is 50 adapted to encounter the sheet close to the margin of plate 35 of the slit mechanism and to slide close against the edge of said plate, so as to form a shear therewith. This results in a clean smooth cut of the sheet without danger 55 of crumpling or tearing the fiber. The cam 28 is so formed as to arrest the downward movement of the cutting-knife at the moment of the completion of the cut—that is, at the moment the required degree of incisions has been 60 secured. At the same moment the slit mechanism begins to open, causing the disengagement of the presser-sections 24 from the sheet, thereby releasing the sheet, so that further cutting becomes impossible. The downward 65 movement of the cutting-knife 13 then con-

tinues to the limit secured by the nuts 10^a engaging boss 11. The folding-blade then continuing the downward movement due to the form of the cam 28 strips the sheet from the cutting-knife and delivers it to the folding-rollers 29 and 30. After the folding-blade has delivered the sheet to the rollers it is raised by the further rotation of cam 28. In its upward movement the arm 1 encounters the lug 9, connected with arm 7, thus carrying the 70 elements connected with said two arms to the initial position. The shape of cam 28 at the point of engagement between arm 1 and lug 9 is such as to retard the upward movement of arm 1 approximate the point of said engagement—that is, the cam movement is a very gradual one just before the engagement of arm 1 and lug 9, so as to prevent a shock or impact as the result of such engagement. 75

What I claim is—

1. In combination with a folding-machine having a reciprocative folding-blade, the mechanism for making a line of incisions in a sheet comprising a series of cutting-points, reciprocative supporting means therefor controlled by the folding-blade, a sheet-supporting plate for coöperating therewith, and sheet-pressing means having lost-motion engagement with said reciprocative supporting means. 90

2. In combination with a folding-machine having a reciprocative folding-blade, the mechanism for making a line of incisions in a sheet comprising a series of cutting-points, reciprocative supporting means therefor controlled by the folding-blade, a pair of horizontal plates spaced apart in the same plane to form a slit for receiving the cutting-points, and means operated relatively with the reciprocative supporting means for depressing the oppositely-disposed edges of said plates. 100

3. In combination with a folding-machine having a reciprocative folding-blade, mechanism for making a line of incisions in a sheet comprising a series of cutting-points, reciprocative supporting means therefor, controlled by the folding-blade, a pair of parallel plates spaced apart in the same horizontal plane to form a slit for receiving the cutting-points, means for pressing the sheet to one of the plates during the cutting operation, and means operated relatively with the reciprocative supporting means for depressing the oppositely-disposed edges of said plates. 110

4. In combination with a folding-machine having a reciprocative folding-blade, the mechanism for making a line of incisions in a sheet comprising a series of cutting-points, reciprocative supporting means therefor, controlled by the folding-blade, slit mechanism 125 for coöperating therewith comprising a pair of parallel plates, means for pressing the sheet to one of the plates during the cutting operation, and means operated relatively with the reciprocative supporting means for depress- 130

- ing the oppositely-disposed edges of the plates and so as to release the sheet from the pressing means.
5. In combination with a folding-machine, cutting mechanism adapted to make incisions in the sheet along the line of the proposed fold and then to bend the sheet to cause the incisions to open to facilitate the removal of the sheet therefrom.
10. 6. In combination with a folding-machine comprising a folding-blade and slit mechanism, means for making incisions in the sheet along the line of the fold and means for operating the slit mechanism at the proper moment to prevent further cutting of the sheet.
15. 7. In combination with a folding-machine, comprising a folding-blade and reciprocating supporting means therefor, a cutting-knife controlled by said reciprocating supporting means and two parallel plates spaced apart in the same horizontal plane to form a slit for receiving the folding-blade and cutting-knife, one of said plates coöperating with the knife to form a shear therewith, and means for rocking the same.
20. 8. In combination with a folding-machine, means for cutting the sheet along the line of the proposed fold and sections of resilient material controlled by the cutting means for engaging the sheet during the cutting operation.
25. 9. In combination with a folding-machine comprising a folding-blade and a cam-controlled reciprocating supporting-arm therefor, a second movable supporting-arm, a cutting-blade and sheet-pressing means supported thereby, and means whereby the folding-blade controls the movement of the second supporting-arm.
30. 10. In combination with a folding-machine comprising a folding-blade and a cam-controlled reciprocating supporting-arm therefor, a cutting-blade, pivotally-movable supporting means therefor, and means whereby the folding-blade controls the movement of the cutting-blade.
35. 11. In combination with a folding-machine comprising a folding-blade and a cam-controlled reciprocating supporting-arm therefor, a cutting-blade, movable supporting means therefor having the same axis of movement as the folding-blade, and means whereby the folding-blade controls the movement of the cutting-blade.
40. 12. In combination with a folding-machine comprising a folding-blade and a spring-actuated cam-controlled reciprocating supporting-arm therefor, a cutting-blade, movable supporting means therefor, and means whereby the folding-blade controls the movement of the cutting-blade.
45. 13. In combination with a folding-machine comprising a folding-blade and reciprocating supporting-arm therefor, a second supporting-arm, a cutting-blade and sheet-pressing means secured thereto, and means for coupling the
- supporting-arm of the cutting-blade with that of the folding-blade.
14. In combination with a folding-machine comprising a folding-blade and a reciprocating supporting-arm therefor, a second reciprocating arm, a cutting-blade and sheet-pressing means supported thereby, and adjustable means for coupling the supporting-arms of the cutting-blade and the folding-blade.
15. The combination of a folding-blade and slit mechanism for coöperating therewith, said slit mechanism comprising a normally horizontal plate extending transversely the line of travel of the sheet, and means operating relatively with the folding-blade for depressing the edge of the plate toward the advancing edge of the sheet to permit the passage of the sheet thereover without obstruction.
16. The combination of a folding-blade and slit mechanism for coöperating therewith, said slit mechanism comprising two parallel normally horizontal plates, and means operating relatively with the folding-blade for depressing the edge of one plate to permit the passage of the sheet thereover without obstruction.
17. The combination of a folding-blade and cutting-knife, and slit mechanism for coöperating therewith, said slit mechanism comprising a normally horizontal plate and means operating relatively with the folding-blade for depressing the edge of the plate to permit the passage of the sheet thereover without obstruction and then restoring the plate to position for coöperating with the cutting-knife.
18. The combination of a folding-blade and cutting-knife, and slit mechanism for coöperating therewith, said slit mechanism comprising two parallel normally horizontal plates and means operating relatively with the folding-blade for depressing the edge of one plate to permit the passage of the sheet thereover without obstruction and then restoring the plate to position for coöperating with the cutting-knife.
19. The combination of a folding-blade and cutting-knife, and slit mechanism for coöperating therewith, said slit mechanism comprising two parallel normally horizontal plates and means, operating relatively with the folding-blade, for depressing the edge of one plate to permit the passage of the sheet thereover without obstruction, then for restoring the plate to position for coöperating with the cutting-knife, and then for tilting both plates to prevent further cutting by the downward movement of the knife.
20. In combination with a folding-machine, sheet-cutting mechanism comprising a beveled knife having its cutting edge in the plane of one side only, a coöperating supporting-plate for the sheet forming a shear with the knife, and means for moving the supporting-plate, after the required incision is made by the

knife, to prevent further cutting of the sheet thereby.

21. In combination with a folding-machine, a cutting device comprising a reciprocative

5 serrated knife having its cutting edge in the plane of one side only, a supporting member for the sheet adapted to form a shear with the knife, and means for moving the supporting-plate, after the required incision is made by the

10 knife, to prevent further cutting of the sheet thereby.

22. In combination with a folding-machine, sheet-cutting mechanism comprising a beveled knife having its cutting edge in the plane of

15 one side only, a coöoperating supporting-plate for the sheet, forming a shear with the knife, means for moving the supporting-plate, after the required incision is made by the knife, to prevent further cutting of the sheet thereby,

20 and pressing mechanism having lost-motion engagement with the knife-supporting means for engaging the sheet on said plate during the cutting operation.

23. In combination with a folding-machine, 25 a cutting device comprising a reciprocative serrated knife having its cutting edge in the plane of one side only, a supporting-plate for the sheet adapted to form a shear with the knife, means for tilting the supporting-plate,

30 after the required incision is made by the knife, to prevent further cutting of the sheet

thereby, and pressing mechanism having lost-motion engagement with the knife-supporting means for engaging the sheet on said plate during the cutting operation.

35

24. In combination with a folding-machine, means for making incisions in the sheet along the proposed fold, comprising a cutting-blade and reciprocative supporting means therefor, a coöperating supporting-plate for the sheet, 40 and presser mechanism, having slidable engagement with the supporting mechanism of the cutting-blade, for pressing the sheet against the supporting-plate during the cutting operation.

45

25. In combination with a folding-machine, means for making incisions in the sheet along the proposed fold, comprising a cutting-blade and reciprocative supporting means therefor, a coöperating supporting-plate for the sheet, 50 presser mechanism, having slidable engagement with the supporting mechanism of the cutting-blade, for pressing the sheet against the supporting-plate during the cutting operation, and means for tilting the plate to release the sheet after the required incision is made by the cutting-blade.

55
